CLAIM

The ornamental design for exhaust pipe and running board set for a mini van, substantially as shown and described.

DESCRIPTION

FIG. 1 is a partial perspective view of the first embodiment of the present design showing of the exhaust pipe and running board set for a mini van;

FIG. 2 is a rear view thereof;

FIG. 3 is a side view thereof, the opposite side being a mirror image thereof;

FIG. 4 is a partial perspective view of a second embodiment of the present design;

FIG. 5 is a rear view of the embodiment of FIG. 4;

FIG. 6 is a partial perspective view of a third embodiment of the present design;

FIG. 7 is a rear view of the embodiment of FIG. 6;

FIG. 8 is a partial perspective view of a fourth embodiment of the present design;

FIG. 9 is a rear view of the embodiment of FIG. 8;

FIG. 10 is a top view of the embodiment of FIGS. 1, 4, 6, 8, 11, and 13;

FIG. 11 is a partial perspective view of a fifth embodiment of the present design;

FIG. 12 is rear view of the embodiment of FIG. 13;

FIG. 13 is a partial perspective view of a sixth embodiment of the present design;

FIG. 14 is a rear view of the embodiment of FIG. 15; and,

FIG. 15 is a side view of the embodiments of FIGS. 4, 6, 8, 11 and 13 the opposite side being a mirror image.

The bottom view is disclaimed herein. Portions of the design shown in broken/dashed lines are for illustrative purposes only and form no part of the claimed design. The illustrated article is not limited to the scale shown.
